CLAIM

The ornamental design for a handheld vacuum cleaner, as shown and described.

DESCRIPTION

FIG. 1 is a front and bottom perspective view of a handheld vacuum cleaner, showing my new design;

FIG. 2 is a front and top perspective view thereof;

FIG. 3 is a rear elevation view thereof;

FIG. 4 is a front elevation view thereof;

FIG. 5 is a left side elevation view thereof;

FIG. 6 is a right side elevation view thereof;

FIG. 7 is a bottom plan view thereof; and,

FIG. 8 is a top plan view thereof.

The broken lines in the figures illustrate portions of the handheld vacuum cleaner that form no part of the claimed design.

1 Claim, 8 Drawing Sheets(56)
